DECORATIVE COVER FOR AN ELECTRIC BULB

Sidney Roth, New York, N. Y.

Application December 5, 1955, Serial No. 39,151

Term of patent 14 years

(Cl. D26—8)

Fig. 1 is a top plan view of a decorative cover for electric bulbs, showing my new design;

Fig. 2 is a side elevational view of the same;

Fig. 3 is a bottom plan view thereof; and

Fig. 4 is a cross-sectional view thereof, taken on the line 4—4 of Fig. 1.

The broken lines shown in Figure 4, are for illustrative purposes only.

I claim:

The ornamental design for a decorative cover for an electric bulb, as shown and described.
